SPECIFICATION forming part of Design No. 24,220, dated April 16, 1895.

Application filed March 14, 1895. Serial No. 541,819. Term of patent 3½ years.

To all whom it may concern:

Be it known that I, WINTHROP L. JACOBS, a citizen of the United States, and a resident of East Orange, in the county of Essex, State 5 of New Jersey, have invented a new and original Design for Carpets, of which the following is a specification.

The accompanying drawing is a face view of a portion of a carpet and border embodying my invention.

The body A is characterized by a series of lines outlining polygonal figures within which are circles surrounding ornamental centers. The circles are connected by straight lines 15 and at the intersection of the lines forming the polygonal figures are small circles.

The border B on its inner portion is characterized by two lines having alternate straight and curved portions between which

are a series of circles. On the inner edge is 20 an ornamental band. Along the outer edge of the border are a series of urn-like figures.

What I claim as my design, and desire to secure by Letters Patent, is—

1. In a design for a carpet, the body A, substantially as shown and described.
2. In a design for a carpet, the border B, substantially as shown and described.
3. The design for a carpet, comprising the body A and border B, substantially as shown 30 and described.

In testimony whereof I have signed my name to this specification in the presence of two subscribing witnesses.

W. L. JACOBS.
